UNITED STATES PATENT OFFICE.

PERCY LLOYD FORBES, OF WEST MIDDLESEX, PENNSYLVANIA.

HAY LOADER.

1,422,432.

Specification of Letters Patent. Patented July 11, 1922.

Application filed May 13, 1921. Serial No. 469,181.

To all whom it may concern:

Be it known that I, PERCY L. FORBES, a citizen of the United States, and a resident of West Middlesex, in the county of Mercer and State of Pennsylvania, have invented certain new and useful Improvements in Hay Loaders, of which the following is a specification.

The present invention relates to an improvement in loaders for hay wagons or the like, and has for its object to provide a device of this character which is of simple and durable construction, reliable in operation, and easy and inexpensive to manufacture; which efficiently loads the hay wagon in a manner to utilize the maximum capacity of the wagon and yet facilitate the unloading thereof; which dispenses with necessity of employing a number of operators; which does not require an independent power plant for its operation; and which is automatic in certain phases of its operation and which requires the simplest manipulation in other phases thereof so that it is necessary to exercise only a minimum degree of attention and effort to control the loader.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a plan view of the machine embodying the invention;

Figure 2 is a view in longitudinal vertical section;

Figure 3 is a side elevational view;

Figure 4 is a fragmentary perspective view, illustrating the control lever and the operating mechanism therefor;

Figure 5 is a similar view of the locking mechanism;

Figure 6 is a detail in fragmentary perspective, illustrating the drive mechanism and associated structure; and

Figure 7 is a fragmentary perspective view of the carriage and track therefor.

Referring to the drawings wherein for the sake of illustration is shown the preferred embodiment of the invention, the numeral 10 designates generally a frame including side bars 11 and which is mounted upon a running gear 12 including rear ground wheels 13 and forward ground

steering wheels 14. A plurality of spaced cross bars 15 are carried by the side bars of the frame 10 and secured thereto and extending parallel with the side bars and adjacent thereto is a pair of longitudinal stringers 16 which are carried by and secured to the cross bars 15.

A track consisting of rails 18 is mounted upon the cross bars, the rails 18 running longitudinally of the frame and parallel and longitudinally to the longitudinal stringers 16. Preferably the rails consist of angle iron, as shown in the drawings. The track extends the entire length of the frame, and at the rear of the track an inclined back 20 is detachably secured.

A carriage, designated generally at 25, is mounted on the tracks and preferably has a lateral extent slightly greater than that of the frame and a longitudinal extent approximately equal to one-half the length of the frame. The carriage includes a frame 26 having a plurality of spaced transverse slats 27 secured thereto, and an inclined front piece 28 which in the forward position of the carriage constitutes the front piece or front wall of the wagon as will herein-after more fully appear. The carriage is mounted on the track by means of grooved wheels 30 rotatably mounted in bearings 31 carried by the frame 26 of the carriage. The bearing 31 is provided with a depending extension 32 having its lower end extended at right angles, as shown at 33, to provide a retaining shoulder which slidably engages the under side of the adjacent rail 18 to retain the track thereon. Preferably four of such wheels and bearings are provided, two being on each side of the carriage and cooperating with the rails of the track, but any desired number may be utilized within the purview of the present invention.

The carriage is in this manner reciprocal on the tracks and with respect to the frame, and when positioned as shown in Figures 1, 2 and 3, it is in its "rearward" position and is then adapted to be loaded. After loading, the carriage is then shifted to its "forward" position and for this purpose it travels along the track to the forward end of the frame, and the rear end of the wagon is then loaded. Locking means is provided for securing the carriage in either forward or rearward position and includes a rock shaft 35 rotatably journaled in the frame of the carriage and having fixed thereto a double ended pawl 36

- having a cupped boss 37 with which a rounded lug 38 formed on the outer end of a blade spring 39 cooperates. The blade spring 39 is normally under tension and its 5 lug 38 presses with considerable force against the boss 37. This spring 39 has a triple action in that when its lug engages one side of the boss of the pawl it urges the pawl in one direction and that when its lug engages 10 the other side of the boss it urges the pawl in the other direction and that when its lug is seated in the cup of the boss it maintains the boss in neutral position. The adjacent rail 18 of the track is provided with spaced 15 series of oppositely disposed ratchet teeth, designated at 40 and 41, respectively with which the double ended pawl cooperates respectively in the forward and rearward position of the carriage.
- 20 Release mechanism is provided for the locking means and includes a crank 42 fixed to the rock shaft 35 and consisting of spaced plates 43 having a pintle 44 journaled therein, on which a grooved pulley 45 is mounted.
- 25 As this crank and pulley also constitute an element of the driving mechanism to be hereinafter fully described, the action thereof will be described in conjunction with the driving mechanism.
- 30 Driving mechanism is provided for the carriage and includes a pair of swinging bearings 50 spaced and pivoted, as at 51, to the longitudinal stringers 16. A winding shaft 52 is rotatably journaled in the swinging bearings 50 and has mounted thereon friction gear wheels 53. Overrunning clutches including ratchet wheels 54 fixed to the winding shaft and pawls 55 pivoted to the friction gear wheels and cooperating 35 with the ratchet wheels serve to connect the friction gear wheels to the winding shaft. These friction gear wheels are preferably provided with surfaces of rubber or other similar material on their peripheries. The driven gear wheels 53 are adapted to be engaged with and disengaged from the ground wheels 13 and when so engaged with the ground wheels are driven therefrom.
- 40 Controlling means is provided for shifting the driven gear wheels into and out of engagement with the ground wheels 13 and comprises an oscillating or rock shaft 57 journaled in bearings 58 carried by the side bars of the frame and having a plurality, preferably three, crank arms 59. Short connecting rods 60 are pivotally connected at one end to two of the crank arms 59 and adjacent their other ends these short connecting rods 60 slidably extend through 45 suitable openings provided therefor in brackets 61 carried by the swinging bearings 50. Adjustable collars 62 are carried by the connecting rod 60 and are adapted to abut the bracket to positively and rigidly connect the brackets and the connecting rod 60 with
- respect to movement in one direction. Coil springs 63 are mounted on the portions of the connecting rods 60 which extend within the brackets 61 and abut these brackets at one end and at the other end abut nuts 64 70 threaded on the ends of the short connecting rods 60. The nuts and springs thus constitute a spring or yielding connection between the short connecting rods and the bearings with respect to movement in one direction, 75 and this yielding or spring connection provides for proper engagement of the driven wheels with the drive wheels and compensates for irregularities or wear. With respect to the connecting rods 60 however the disengagement of the driven wheels from the ground wheels is positive and rigid so that the yielding connections are made use of only when it is advantageous to do so and they are not subjected to wear at other 80 times.
- 85 An operating lever 65 for the drive mechanism is pivotally mounted, as at 66, upon a strap bearing 67 provided at the forward end of the machine and the lower end of the operating lever is pivotally connected, as at 68, to one end of a connecting rod 69. The other end of the connecting rod slidably extends through an eye 59^a provided on one of the crank arms 59 of the rock shaft 57 90 and a collar 70 is fixed on the connecting rod and abuts the crank arm to positively move the crank arm in one direction. A coil spring 71 is arranged on the end of the connecting rod which projects beyond the eye and abuts the crank arm 59 at one end and a nut 72 at the other end, the nut 72 being threaded on the connecting rod 69. The spring and nut thus provide a resilient 95 or yielding connection between the crank arm and the connecting rod with respect to motion in one direction. A detent 75 is pivotally mounted on the operating lever 65 by means of a pivot pin 76, and is adapted to cooperate with the ratchet teeth 77 carried 100 on the plates 78 and secured to the adjacent cross bar 15. A spring 79 coacts with the detent and urges it into engagement with the teeth of the ratchet.
- 105 Tripping mechanism is provided for releasing the detent 75 from engagement with the ratchet teeth 77 and for swinging the operating lever 65 so as to disengage the driven friction gear wheels of the driving mechanism from the ground wheels and thereby throw the driving mechanism out of 110 operation. For this purpose, a curved arm 80 is integrally formed with or otherwise secured with the detent 75 and extends rearwardly from the operating lever. A trip or 115 projection 81 is carried by the frame of the carriage and is adapted to coast with the curved arm 80 to swing the detent upwardly 120 against the tension of the spring 79 and release it from engagement with the ratchet 125 130

teeth and thus permit the carriage which subsequently engages the operating lever, to swing the operating lever so as to release the driving mechanism.

5 Motion transmission means is provided for transmitting the motion of the winding shaft 52 to the carriage 25 for moving the same from one position to the other and comprises a pair of winding drums or spools 10 85 carried by the winding shaft upon which cables 86 are wound when the winding shaft is rotated. These cables extend to the front of the vehicle and they are then trained around pulleys 84 and pulleys 87 and extend 15 rearwardly of the vehicle and at their rear ends they are connected or trained around the pulley 45 and thus the cables are connected to the carriage. It is obvious that as the winding shaft is rotated and the cables 20 are wound upon the winding drums thereof they will exert a pull upon the pulley 45 and advance the carriage from its "rearward" to the "forward" position. It is to be noted that when the carriage is in its rearward position as shown in Figures 2 and 3, it is locked in this position by means of a double ended pawl 36 engaging the ratchet teeth 41 and that at the same time the crank 43 which carries the pulley 45 is depending substantially vertically. Consequently, when the 30 driving mechanism is thrown into gear and the vehicle is advanced the pull which is exerted on the pulley 45 is first effective to swing the crank 43 upwardly to the horizontal and thus to rotate the rock shaft 35 in a counterclockwise direction and release the double ended pawl 36 from engagement with the ratchet teeth 41, thus releasing the carriage. Following this action the pull is then 40 effective to shift the loaded carriage from its rearward position to its forward position. When the carriage is being shifted from its rearward to its "forward" position, the pawl slides along the track so that as soon as the 45 carriage reaches its forward position this pawl snaps into the forward series of ratchet teeth, designated at 40, and locks the carriage in its forward position. After the wagon has been completely loaded, the load 50 transported and unloaded, and it is desired to again shift the carriage back to its initial position for another loading operation, it is necessary to manually shift the double ended 55 detent 36 for the rock shaft so as to release this detent from its forward series of ratchet teeth. When the carriage is unloaded it may be readily shifted by hand from its forward to its rearward position.

In this manner the wagon may be loaded 60 without the necessity of placing several operatives on the wagon for as soon as the carriage is loaded it is shifted to the forward end of the vehicle and the rearward end of the vehicle is then loaded. Moreover this 65 provides not only for a properly constructed

load, as the hay which makes up the load consists substantially of two sections, although these sections abut each other, and this facilitates the unloading operation.

I claim:

1. In a device of the character described, a frame, ground wheels therefor, tracks on said frame, a carriage on said tracks, driving mechanism for said carriage including a pair of swinging bearings, a winding shaft 70 journaled in said bearings and a pair of driven friction gear wheels connected to said winding shaft and engageable with said ground wheels, controlling means for said drive mechanism adapted to yieldingly move 75 said gear wheels into operative engagement with said ground wheels and to positively move said gear wheels out of engagement with said ground wheels, and motion transmission means between said winding shaft 80 and said carriage.

2. In a device of the character described, a frame, ground wheels therefor, tracks on said frame, a carriage reciprocable on said tracks, driving mechanism for said carriage 90 including a swinging bearing, a winding shaft journaled in said bearing, and driven friction gear wheel connected to said winding shaft and engageable with said ground wheels, controlling means for said drive 95 mechanism including a rock shaft having crank arms, a connecting rod between one of said crank arms and said swinging bearing, an operating lever, a connecting rod between said operating lever and the other of said 100 crank arms of said rock shaft, and motion transmission means between the winding shaft and the carriage.

3. In a device of the character described, a frame, ground wheels therefor, a carriage 105 movable on said frame, and driving mechanism for said carriage including a pair of swinging bearings, a winding shaft journaled in said bearings, a pair of driven friction gear wheels on said winding shaft 110 and engageable with said ground wheels, overrunning clutches connecting said driven gear wheels to said winding shaft, controlling means for said driving mechanism, and motion transmission means between the winding shaft and the carriage including 115 winding drums carried by the winding shaft, and cables wound on said drums and connected with said carriage.

4. In a device of the character described, 120 a frame, ground wheels therefor, a carriage movable on said frame and driving mechanism for said carriage including a pair of swinging bearings, a winding shaft journaled in said bearings, a pair of driven friction gear wheels connected to said winding shaft and engageable with said ground wheels, controlling means for said driving mechanism including a rock shaft having 125 crank arms, connecting rods pivotally connected 130

- nected at one end to certain of said crank arms and having spring connections at their other ends to said swinging bearings, and an operating lever for said rock shaft.
5. A device of the character described, in combination, ground wheels, a driving mechanism including a pair of swinging bearings, a winding shaft journaled therein, a pair of driven gear wheels connected to the winding shaft and engageable with the ground wheels, and controlling means including a rock shaft having crank arms, a pair of connecting rods pivotally connected to certain of said crank arms at one end, brackets carried by the swinging bearings and slidably receiving the free ends of said connecting arms, adjustable collars carried by said connecting rods and rigidly engaging said brackets with respect to movement in one direction, coil springs arranged on the portions of the connecting rods extended within said brackets and abutting said brackets at one end, nuts threaded on said connecting rod and engaging the other end of said spring.
6. A device of the character described, in combination, ground wheels, a driving mechanism including a pair of swinging bearings, a winding shaft journaled therein, a pair of driven gear wheels connected to the winding shaft and engageable with the ground wheels, and controlling means including a rock shaft having crank arms, a pair of connecting rods pivotally connected to certain of said crank arms at one end, brackets carried by the swinging bearings and slidably receiving the free ends of said connecting arms, adjustable collars carried by said connecting rods and rigidly engaging said brackets with respect to movement in one direction, coil springs arranged on the portions of the connecting rods extended within said brackets and abutting said brackets at one end, nuts threaded on said connecting rod and engaging the other end of said spring, an operating lever, and a connecting rod pivotally connected at one end to said operating lever and having a yielding connection at its other end to the other of the cranks of said rock shaft. 50
7. In a device of the character described, tracks, a carriage reciprocable on said tracks, and locking means for the carriage including a rock shaft mounted on the carriage, a double ended pawl fixed to the rock shaft, and spring means for urging either end of said pawl into operative position, said track having spaced series of oppositely disposed ratchet teeth with which said double ended pawl is adapted to be selectively engaged. 55
8. In a device of the character described, tracks, a carriage reciprocable on said tracks, and locking means for the carriage including a pawl pivoted to said carriage, 60 said tracks having spaced ratchet teeth with which said pawl is selectively engageable.
9. In a device of the character described, a frame, a carriage reciprocable on said frame, locking means for said carriage including a rock shaft journaled on the carriage, locking pawls controlled by said rock shaft, driving mechanism, motion transmission means between the driving mechanism and the carriage including a cable and a 70 crank connected to the rock shaft of the carriage and engaged by said cable whereby the driving mechanism controls the locking mechanism so as to release the same prior to imparting movement to said carriage. 75
10. In a device of the character described, a frame, a pair of ground wheels, a carriage reciprocable on said frame, driving mechanism for said carriage including a pair of swinging bearings, a winding shaft journaled in said bearing, a pair of friction gear wheels connected to the drive shaft and engageable with the pair of ground wheels, and controlling mechanism for said driving mechanism. 80
